(57) **CLAIM**

The ornamental design for a protective mat, as shown and described.

DESCRIPTION

FIG. 1 is a top plan view of a protective mat showing our new design; and,

FIG. 2 is a bottom plan view thereof.

The broken showings throughout the figures are representative of stitching. The bottom plan views of the first and second embodiments are identical.

1 Claim, 2 Drawing Sheets

FIG. 1

FIG. 2
